CIRCUIT CONTROLLING DEVICE

Albert B. Rypinski, Laurelton, N. Y., assignor to
 Metropolitan Device Corporation, Brooklyn,
 N. Y., a corporation of New York

Application June 7, 1947, Serial No. 753,193

3 Claims. (Cl. 200—88)

1

The invention herein disclosed relates to a circuit controlling device that may be operated manually to open and close an electrical circuit, but which operates automatically to open a closed circuit upon continued overloads and short circuits. More particularly, the invention relates to a circuit breaker of the kind mentioned in which a movable switch element is retained against the action of biasing means by a detent and releasable latch.

An object of the invention is to provide a circuit breaker of the kind mentioned in which a magnetically affected element is forcibly attracted to the latch and in a direction to release the latch upon a sudden rise in current flowing through the circuit breaker. Another object of the invention is to provide a circuit breaker of the kind mentioned in which a magnetically affected element is forcibly attracted to a bimetallic latch upon a sudden rise in current flowing through the bimetallic latch so that on short circuit, the latch is rapidly released.

The foregoing objects and certain advantages inherent in the invention that will hereinafter appear are realized in the embodiment of the invention illustrated in the accompanying drawing and described in detail below, from which description a clear understanding of the invention may be had.

The drawings include:

Fig. 1 which is a plan of a circuit breaker embodying the invention;

Fig. 2 which is a transverse section of the same taken on the line 2—2 of Fig. 1;

Fig. 3 which is a sectional, side elevation taken on the line 3—3 of Fig. 1;

Fig. 4 which is a sectional, side elevation taken on the line 4—4 of Fig. 1;

Fig. 5 which is an enlarged, side elevation of the movable switch element, partly broken away; and

Fig. 6 which is a sectional elevation of the same taken on the line 6—6 of Fig. 5.

The circuit breaker illustrated in the drawings essentially includes a case and operating parts that are housed within the case. The case A for the circuit breaker is open at the bottom and has an opening 1 through the top for a finger piece 2 by means of which the circuit breaker may be manually actuated. A base B serves as a closure for the bottom of the case and as a support for stationary contacts 3 and 4, associated with connecting pieces 5 and 6 and terminals 7 and 8. These case and base together form a complete enclosure for the circuit breaker ex-

2

cept for vents 9 and 10 extending vertically through the case to permit the free passage of gases generated by arcs formed within the case.

The operating mechanism, in general, includes two movable elements, a manually operative element or handle C from which the finger piece 2 extends, and a switch element or rotor D. The handle consists of a disk-like wall 11 from which a shaft 12, formed integral therewith, extends. An axially extending flange 13 is formed at one portion of the handle, the outer portion in the assembled circuit breaker, and extends from the wall 11. The finger piece 2 extends radially from this flange through the opening in the case. The rotor is partially encased within the handle and is rotatably mounted upon the shaft 12 which in turn is rotatably mounted in a slide 14 received in a complementary groove in one side wall of the case, and in the arcuate end of a slot 15 in the opposite side wall.

A spring element acts upon the handle and rotor to effect independent movement thereof towards "off" or open-circuit position. This spring element consists of two torsional spring sections 16 and 17, one on each side of a central loop 18 extending substantially tangentially of the spring. The end of the spring section 16 is received in a groove or keyway in the shaft 12 and the end of the section 17 is received in a groove in the rotor. Under normal conditions, the handle, when moved to the "on" position, is restrained against the action of the spring section 16, which acts to urge the handle toward "off" position, by a latching lever 19 that enters in a recess 20 in the flange on the handle and engages the end wall of the recess.

This latching lever 19 is resiliently urged into latching relation with the end of the slot or recess 20 by the spring loop 18 which engages the latching end of the lever. The lever is pivoted between its ends upon a pivot pin 21 that extends from the slide 14 in which the shaft 12 is journaled. A cam surface 22 on the rotor is arranged to engage the end 23 of the lever when the rotor moves to "off" position. Upon engagement of the end of the lever by the cam surface 22, the lever is withdrawn from the recess in the handle and the handle is thus released to move to "off" position under the action of the spring section 16.

The rotor, normally, is latched, in a manner hereinafter described, to the handle so that when the handle is moved to "on" circuit position, the rotor moves with the handle. Likewise, the latching arrangement is such that if the handle be

moved to "off" circuit position, the rotor under the action of the spring section 17 will follow the handle to the "off" position.

The rotor carries switch contacts 24 and 25 which engage respectively, in the "on" position, with the stationary contacts 3 and 4. When the rotor moves to the "off" circuit position, the contacts 24 and 25 move away from the stationary contacts. Normally, the section 17 of the spring and the stationary contacts exert a force tending to rotate the rotor to the "off" position. The stationary contacts are mounted and arranged so as to have a certain amount of resiliency and are positioned with respect to the contacts on the rotor so that they are under tension in the "on" circuit position of the rotor.

The rotor is provided with current-releasable means for effecting the release of the rotor from the handle upon continued overloads or short circuit. It is with this current releasable means, as arranged in a circuit breaker of this kind, that the invention of this application is primarily concerned.

The latching arrangement by which the rotor is normally secured to the handle includes a detent 26 and a bimetallic element 27. The detent consists of a dog-pointed, hardened set screw that is threaded in an opening in the flange 13, and it extends from the flange parallel to the axis of circuit breaker mechanism. The end 28 of the set screw acts as a detent and is engaged, under normal conditions by the detent-engaging end 29 of the bimetallic element 27.

Each of the rotor contacts 24 and 25 has a reduced rounded extension, 30 and 31 respectively, which passes through the rotor wall. The end sections of these extensions are further reduced in diameter and have flanged, insulating bushings, such as the bushing 32 (Fig. 6) thereon, and the ends of the bimetallic element 27, which is substantially of the shape of an inverted V, are secured on these extensions between the flanges of the bushings and headed-over ends of the extensions. The ends of the bimetallic element are thus secured at the face of the rotor and electrically connected to the contacts 24 and 25, i. e. the bimetallic is connected across the contacts so that current through the breaker flows through the bimetallic element. The detent-engaging end section 29 of the bimetallic element extends radially to a point beyond the end 28 of the set screw 26. One edge of the detent-engaging end section, that which engages the detent, is cut away as shown to conform to the shape of the detent, and the edge may be rounded to provide a point contact with the detent and so minimize friction tending to retard warping of the bimetallic element. The opposite edge of the detent-engaging end section is wedge-shaped and bent away from the detent to form a lead-in and so permit ready relatching after the bimetal has escaped and cooled. Under bias of the spring, the bimetal engages in latching relation the detent end 28 of the screw 26 to effect movement of the rotor with the handle, under normal conditions, from open-circuit to closed-circuit position. By turning the screw 26, the extent of engagement between the bimetallic element and detent may be adjusted.

The bimetallic element is held away from the face of the rotor as shown. Between the bimetallic element and the rotor an iron armature 33, in the shape of an inverted V, is mounted on the insulating bushings (32, Fig. 6) on the

extensions 30 and 31 so that it may pivot thereon. The iron armature is shaped the same as the bimetallic element, except that it is without a detent-engaging end section.

5 The normal operation of the circuit breaker is by the heating and warping of the bimetallic element. This heating and warping occurs when excess current passes through the bimetallic element. When warped the bimetallic element becomes released from the detent and releases the rotor. On a sudden rise in value of the current, such as occurs on short circuit, the magnetic field set up by the current in the bimetallic element causes the hinged iron armature to be attracted at its free end, as any armature is attracted by a solenoid, and the armature delivers a blow to the bimetallic element at the detent-engaging section thereof and in the direction to free the bimetallic element from the detent. If perchance the blow delivered by the armature is insufficient to free the bimetallic element immediately, its pressure on the bimetallic element will follow the pulsations of the alternating current, and the combined warping of the bimetallic element and the magnetic vibratory pressure will quickly disengage it.

When the bimetallic element is released from the detent, either by warping, by a blow from the armature, or by both, the rotor or switch 30 element moves, under the action of the spring to "off" circuit position. Movement of the rotor releases latching lever 19, and the handle follows the rotor to "off" circuit position where the rotor and handle are relatched through the bimetallic element. If the release of the bimetallic element occurred by virtue of a blow from the armature, the relatching may occur immediately; if it occurred by warping of the bimetallic element, then the bimetallic element must cool before relatching occurs.

From the foregoing description of the embodiment of the invention illustrated in the drawing, it will be apparent that by this invention there is provided a circuit breaker in which a magnetically affected armature is forcibly attracted to the releasable latch in a direction to release the latch and effect a rapid opening in the breaker on a sudden rise in the value of the current or on short circuit.

It will be obvious that various changes may be made by those skilled in the art in the details of the embodiment of the invention illustrated in the drawings and described in detail above within the principle and scope of the invention as defined in the appended claims.

55 I claim:

1. In a circuit controlling device of the kind described, the combination comprising a movable switch element, spaced switch contacts carried by the switch element, a bimetallic element carried by the switch element, connected across the switch contacts and having a detent-engaging end section movable with respect to the switch element, bias means for moving the switch element in one direction, a detent positioned to 60 retain the switch element against movement under the action of said bias means when engaged by the detent-engaging end section of the bimetallic element, and a magnetically attracted armature pivotally mounted on the switch element and positioned to be forcibly attracted to and strike the detent-engaging end section of the bimetallic element in a direction to release the bimetallic element from the detent upon a sudden rise in current flowing through the bimetallic element.

2. In a circuit controlling device of the kind described, the combination comprising a movable switch element, spaced switch contacts carried by the switch element, a bimetallic element carried by the switch element, connected across the switch contacts and having a detent-engaging end section movable with respect to the switch element, bias means for moving the switch element in one direction, a fixed detent positioned to retain the switch element against movement under the action of said bias means when engaged by the detent-engaging end section of the bimetallic element, and a magnetically attracted armature between the switch element and the bimetallic element, and pivoted on the switch element and positioned to be forcibly attracted to and strike the detent-engaging end section of the bimetallic element in a direction to release the bimetallic element from the detent upon a sudden rise in current flowing through the bimetallic element.

3. In a circuit controlling device of the kind described, the combination comprising a movable switch element, spaced switch contacts carried by the switch element, a bimetallic element carried by the switch element, connected across the switch contacts and having a detent-engaging end section movable with respect to the switch element, bias means for moving the switch element in one direction, a fixed detent positioned

5 to retain the switch element against movement under the action of said bias means when engaged by the detent-engaging end section of the bimetallic element, and a magnetically attracted armature between the switch element and the bimetallic element, pivoted on the connections between the switch contacts and the bimetallic element and positioned to be forcibly attracted to and strike the detent-engaging end section 10 of the bimetallic element in a direction to release the bimetallic element from the detent upon a sudden rise in current flowing through the bimetallic element.
